DESIGN FOR A GAME DART

Otis E. Keene, Bronx, N. Y.

Application October 7, 1941, Serial No. 103,668

Term of patent 14 years

To all whom it may concern:

Be it known that I, Otis E. Keene, a citizen of the United States, residing at Bronx, in the county of Bronx and the State of New York, have invented a new, original, and ornamental Design for a Game Dart, of which the following is a specification, reference being had to the accompanying drawing, forming part thereof.

Fig. 1 is a perspective view of a game dart, showing my new design;

Fig. 2 is an edge elevational view thereof; and
Fig. 3 is a front end elevation.

I claim:

The ornamental design for a game dart, substantially as shown.

OTIS E. KEENE.
